UNITED STATES PATENT OFFICE

CARL H. BISSELL, OF SYRACUSE, NEW YORK, ASSIGNOR TO CROUSE-HINDS COMPANY,
OF SYRACUSE, NEW YORK, A CORPORATION OF NEW YORK

AUTOMATIC EMERGENCY SELECTIVE SWITCH

Application filed June 13, 1928. Serial No. 285,029.

This invention relates to signaling systems as traffic signals and has for its object an automatic emergency selective switch for throwing on a particular set of signals to the exclusion of the other signals for a predetermined period of time, as for instance throwing on the stop signal to the exclusion of the other signals and keeping them on for predetermined periods, which switch is particularly simple and compact in construction and highly efficient in use.

The invention consists in the novel features and in the combinations and constructions hereinafter set forth and claimed.

15 In describing this invention reference is had to the accompanying drawings in which like characters designate corresponding parts in all the views.

20 Figures 1 and 2 are side elevations of the selective switch showing respectively, the motor, intermittent switch, clutch and motion transmitting means driven by the motor, and the selective controlling switch, the casing being omitted in both views, one view being 25 a continuation of the other.

Figure 3 is a front elevation or face view of the controlling switch and contiguous parts.

30 Figure 4 is an end elevation of a complete switch, part of the case being removed, showing particularly the motor.

Figure 5 is an opposite side elevation of the motor and contiguous parts from that seen in Figure 4.

35 Figure 6 is a fragmentary detail view of the locking means for the operating means of the controlling switch.

40 Figures 7 and 8 are respectively an elevation and end view of a portion of the clutch and the electro-magnet for operating it.

Figure 9 is a face view of the other section of the clutch for tripping the locking means, the trip also being shown.

45 Figure 10 is a diagrammatic view of the wiring of the instrument.

In street traffic signals, it is desirable to, at times, stop all traffic for a predetermined period of time to permit the passage of a 50 fire apparatus or other emergency vehicle

through the section of the city provided with the traffic signals.

The switch is located at a central station and the operator knows the approximate time it will take the emergency vehicle to travel 55 from its station to a predetermined point as a fire alarm box, and how long it will be necessary to stop traffic to permit the passage of the vehicle.

This automatic emergency selecting switch 60 provides means for setting all stop signals to the exclusion of the "go" and warning signals for a predetermined period of time as 15, 30, or 45 seconds before the traffic signals again take up their normal operation.

65 The switch here shown is designed to set the stop signals for periods of time which are multiples of fifteen from 15 to 120 seconds. The traffic signals are usually red lamps for "stop", green lamps for "go" with 70 an intermediate warning amber signal.

75 The switch here illustrated operates to set all the red signals to the exclusion of the green and amber for periods of time from 15 to 120 seconds.

80 This automatic emergency selective switch comprises generally an electric motor connected in a feed circuit, a normally open controlling switch for controlling the flow of current through the motor and through a signal circuit for different selected periods of time, the switch being manually operable to closed position and means operated by the motor for automatically controlling the opening of the switch.

85 More specifically, the selective switch includes an electric motor, a normally open switch for controlling the flow of current through the motor and through the signal circuit comprising a conductor connected in the signal circuit and having a plurality of contacts spaced apart, and movable operating means connected in the feed circuit and operable to selectively engage the contacts, locking means for holding the operating means, means tending to actuate the operating means to open the switch, a trip operable to disengage the operating means from the contact with which it is engaged, the trip being normally arranged in a predetermined 90 95 100

starting position and having means for returning it to such starting position, motion transmitting means between the motor and the trip whereby when the trip disengages the operating means from the contact with which it is engaged and the feed and signal circuits are broken, the trip returns to its starting position for the next operation.

1 designates the base on which the parts of the switch are mounted.

2 is a detachable housing or cover mounted on the base, the rear wall of the housing being removed in Figure 4.

3 designates the motor and the motor here shown is a disk induction motor.

4 designates the disk which is mounted upon a shaft 5 suitably supported in uprights or brackets 6, 7 mounted on the base plate. The disk is here shown having a hub 8 on one side thereof to which the shaft 5 is secured as by a key or screw 9, the shaft at its other end coaxing with an adjustable cone bearing 10 carried by the upright 6.

11 and 12 are the coils of the magnet of the motor, these coils having cores 13, 14 arranged in juxtaposition to the disk to cause the disk to rotate when the coils are connected in the feed circuit. The cores on which the coils are mounted are supported in any suitable manner by brackets 15 and 16 rising from the base 1. The construction of the motor per se forms no part of this invention.

The conductor of the controlling switch is here shown as annular in form so that the contacts are arranged in circular series.

17 designates the conductor which is mounted on a block of insulation 18 on the base 1.

19 designates the contacts spaced apart and preferably equidistant apart on the conductor. These contacts are shown as pins extending radially toward the center of the conductor.

45 In the illustrated embodiment of my invention, the movable operating means operable to selectively engage the contacts comprises a movable switch member, one for each contact and as the contacts are arranged in a circular series, the switch members are arranged in a circular series and mounted on and in electrical contact with a circular conductor common to all of them.

20 is the circular conductor of the operating means, this being mounted upon the base 18 of insulation opposed to and in axial alignment with the conductor 17.

21 designates the movable switch members, these being slidably mounted in the conductor 20 and projecting through the same and having terminals movable into and out of engagement with the contacts 19. These members are here shown as rods slidable through bosses or hubs 22 formed on the conductor 20, these rods extending through a face plate 23

at the front of the base and having operating buttons 24 on the outside of the face plate. The buttons 24 slide through holes in the face plate 23. The rods 21 are provided on their ends between the conductors 17 and 20 with heads 25, which are provided with terminals 26 for engaging the contact pin 19 of the conductor 17. Coil springs 27, interposed between the buttons 24 and the bosses 22, return the switch members 21 to their normal position assumed when the switch is open. The rods 21 are held from turning by pins 28 extending through the bosses 22 and in the slots 29 in the rods.

The locking means for holding the operating means or the rods 21 in their operated position comprises a latch 30 pivoted at 31 to the head 25 of each member 21 and movable into interlocking engagement with the companion contact or pin 19, this latch carrying the terminal 26. The latch is normally pressed by a spring 32, see Figure 6. Each head 25 is bifurcated and the latch 30 and spring 32 located between the bifurcations thereof.

The buttons 24 are provided with suitable time indications as 15, 30, 45 etc. Obviously, when any one of the buttons 24 is depressed, the terminal 26 thereof will engage the companion contact 19 and as the rods 21 are in electrical contact with the conductor 20, the circuit is closed between the conductors 20 and 17, the latter being connected in the signal circuit and the former in the feed circuit as will be hereinafter described.

33 designates the trip for disengaging any one of the latches 30 from its companion pin 19. As the conductor 17 is circular or as the contacts 19 are arranged in a circular series, this trip is movable about an axis coaxial with the axis of the conductor 17, it being normally arranged in a predetermined starting position and hence, movable different distances by the motor from its starting position into engagement with the various contacts 19.

This trip is here shown as an arm mounted upon a hub 34 actuated by the motor as will be hereinafter described, the hub being mounted upon a shaft 35 having cone bearings at one end, the bearing being in the end of a screw 36 adjustably mounted on a hub 37 at the center of the conductor 17. This hub is shown as carried by a pair of diametrically extending spokes 38 in the conductor 17. The other end of the shaft 35 is mounted in a bearing in the bracket 7. The trip is provided with means as a weighted end 39 for returning it to its starting position when the motor stops, that is, after the latch 30, which is in operated position, is tripped to permit the controlling switch to open. Preferably, the trip is actuated by the motor through motion transmitting means including a clutch having normally separated sections and means tending to separate them, the engage-

ment of the sections being controlled by the operation of any one of the switch members 21.

In the illustrated embodiment of my invention, the motion transmitting means comprises a worm 40 on the motor shaft 5 meshing with a worm gear 41 on a transverse shaft 42, see Figure 5, supported by the bracket 7, the shaft 42 having a worm 43 thereon meshing with the worm gear 44 on the shaft 35 on which the hub 34 of the trip is mounted. As a clutch is employed, this hub 34 is loosely mounted on the shaft 35.

45 designates one section of the clutch 15 which is rotatable with the hub 34, Figure 1, the other section of the clutch carried by an arm 47 on a hub 48 keyed to the shaft 35, this section 46 being in the form of a lever having a tooth 49 movable into and out of engagement with the teeth 50 on the clutch section.

The movement of this clutch section or lever 46, as before stated, is controlled by the movement of any one of the push buttons 24 or rods 21. In the illustrated embodiment of 25 my invention, this movement of the clutch section 46 is effected by an electromagnet connected in the feed circuit by the closing of the controlling switch, that is, by the bringing of any one of the terminals 26 into engagement with its contact 19.

51 designates the electromagnet having outside metal heads 52 arranged to attract an armature arm 53 of the lever 46 when the circuit is closed through the coil 51, and hence move the lever 46 on its pivot into engagement with the teeth 50 of the clutch section 45.

The magnet 51 is stationary and carried by brackets 7 concentric with the shaft 35 on which the hub 48 of the arm 47 is mounted, which carries the clutch section or lever 46. When the circuit is closed through the motor and the magnet by operating any one of the push buttons 24, the clutch section or lever 46 will be attracted by the magnet and moved 45 into clutching engagement with the locked clutch section 45, and the shaft 35 will be actuated by the motor, and the motion transmitted through the lever 46 and clutch section 45 to the hub arm 33. The armature arm 53 moves planetarily around the periphery of the stationary magnet while the clutch section or lever 46 is engaged with the section 45. The electromagnet clutch forms the subject matter of another application Sr. No. 274,744 filed May 3, 1928.

After the latch is tripped, the spring 27 opens the switch so that the motor and the electromagnet 51 are de-energized and hence, the arm 46 released from the teeth 50 of the clutch section 45 so that the trip swings under the influence of its weight 39 to its normal or starting position. The movement of the lever 46 by the electromagnet is against the action of a returning spring 54, Figure 8.

65 Preferably an intermittent or flashing

switch is arranged in the signal circuit. 55 designates the flashing switch, that here shown being a mercury switch. This intermittent switch may be of any type and comprises a rock arm 56 pivoted at 57 to the bracket 7 and carrying a support 58 on which is mounted a container 59 in which the mercury is located and terminals exposed to the mercury at both ends of the container. As the action of these mercury switches is well known, further description is thought to be unnecessary.

The rock arm 56 is actuated by motion transmitting means connected to the motor, this motion transmitting means including a 80 cam 60 coacting with a follower 61 on the lever 56, this cam being mounted upon the shaft 42 so that during the actuation of the motor, the mercury switch is oscillated causing the signals to be flashed.

85 Suitable binding devices 62, 63, 64 and 65 are mounted on the base outside the casing 2 for connection in the feed and signal circuits.

In operation, when one of the buttons 24 is depressed, the corresponding contact 26 and latch 30 are moved into engagement with one of the contacts 19 whereupon the current passes from binding device 62, wire 66 to conductor 20 thence through the rod 21 of the push button 24, latch 30 and terminal 26 to the companion contact 19 thence through wires 67 and 68 through the coils 11 and 12 of the motor to actuate the motor and from these coils through wire 69 to the binding device 63.

90 For the purpose of illustration, the binding devices 62 and 63 may be considered as plus and minus and the binding devices 64 and 65 as plus. The current also passes from the wire 67 through branch wire 70 to the coil 51 of the electromagnet through wires 71 and wire 72 to the wire 69 and negative binding post 63. The current also passes from the wire 67 through branch wire 73 through the mercury switch to wire 74 thence to wire 75 to binding post 65 to the signal circuit connected to the binding post 63, 64, 65. Also connected in circuit with the wires 69 and 75 is a lamp 76 located in the face plate 23 at the center of a series of push buttons 24, this lamp 76 operating under the same conditions as the lamps in the signal circuit. The wire in the signal or load circuit connected to the binding devices 64, 65 and 63 usually operate relays which control the lamps in the signal circuit but whether they operate relays or control the current directly to such lamps is immaterial to this invention.

105 110 115 120 125 The operator at the central station knows the time it will take the fire apparatus or other emergency vehicle to go from its station to a call box or other known locality and presses any one of the buttons 24 depending upon the amount of time it will take 130

for the apparatus to make the trip. The pressing of any one of these buttons 24 causes the terminal 26 and latch 30 to coact with the corresponding contact 19 thus closing the circuit through the motor coils 11 and 12 and electromagnet coils 51 which operate the clutch, and through the mercury switch so that the light 76 is illuminated and flashed as well as the lights in the signal circuit. This operation continues automatically until the trip 33 releases the latch 30 which is in operated position, thus opening the controlling switch or the circuit between the conductor 17 and conductor 20 so that the motor stops and the trip is declutched from the motor and returns to its starting position for the next operation. This opening of the controlling switch takes place at a predetermined time dependent upon which of the push buttons 24 is depressed.

What I claim is:

1. In an automatic emergency selective switch, a suitable frame, a load circuit conductor carried by the frame and having a series of contacts spaced apart, normally open switch means operable to selectively engage the contacts, means tending to actuate the switch means to open the same, locking means for holding the switch means engaged with the selective contact, a trip movable along the series of contacts to trip the locking means, an electric motor in circuit with the switch means, motion transmitting means between the motor and the trip to actuate the trip along the series of contacts, when the switch means is in operated position, the trip comprising normally separated clutch sections and means tending to separate them, and means controlled by the movable switch means to engage said clutch sections when the switch means is moved into engagement with one of the contacts.

2. In an automatic emergency selective switch, a suitable frame, a load circuit conductor carried by the frame and having a series of contacts spaced apart, a plurality of switch members, one for each contact, and each operable to engage its companion contact, means tending to actuate the switch members to separate them from the contact, locking means for holding each switch member engaged with its contact, a trip common to all the locking means and movable along the series of contacts to trip the locking means, an electric motor in circuit with all the switch members, motion transmitting means between the motor and the trip to actuate the trip along the series of contacts when one of the switch members is in operated position, the trip having means for returning it to starting position, said motion transmitting means comprising normally spaced clutch sections and means tending to separate them and means controlled by the movable switch members to engage said

clutch sections when any one of the switch members is moved into engagement with its companion contact.

3. In an automatic emergency selective switch, a suitable frame, an annular load circuit conductor carried by the frame and having a series of contacts spaced apart, normally open switch means operable to selectively engage the contacts, means tending to actuate the switch means to open the same, locking means for holding the switch means engaged with the selected contact, a trip normally arranged in a predetermined starting position and movable about an axis concentric with the annular conductor over the series of contacts to trip the locking means and release the switch means from the contact with which it is engaged, a motor connected in circuit with the switch means whereby the closing of the motor circuit is controlled by the switch means, the motion transmitting means comprising normally separated clutch sections and means tending to separate them, and means controlled by the operation of the switch means to engage the clutch sections.

4. In an automatic selective switch, a suitable frame, an annular load circuit conductor mounted on the frame, and having a series of spaced apart contacts, a second annular conductor spaced apart from the former conductor substantially concentric therewith, a plurality of movable switch members in electrical contact with the second annular conductor and paired respectively with the contacts, each switch member having means for engaging one of the contacts, locking means for holding each switch member engaged with its companion contact, means tending to actuate each switch member to its open position, a trip normally arranged concentric with said conductors, and in a predetermined starting position and movable to trip the locking means of the switch member in engagement with its contact, a motor connected in circuit with the second conductor whereby the closing of any one of the switch members closes the circuit to the motor, motion transmitting means between the motor and the trip to move it about its axis from starting position into engagement with the locking means in locked position, said motion transmitting means comprising normally spaced apart clutch sections and means tending to separate them and means controlled by each of the switch members to engage the clutch sections.

5. In an automatic emergency selective switch, a suitable frame, a load circuit conductor carried by the frame and having a series of contacts spaced apart, normally open switch means operable to selectively engage the contacts, means tending to actuate the switch means to open the same, locking means for holding the switch means engaged with the selected contact, a trip movable

along the series of contacts to trip the locking means, an electric motor in circuit with the switch means, motion transmitting means between the motor and the trip to actuate the trip along the series of contacts, when the switch means is in operated position, the trip comprising normally separated clutch sections, and means controlled by the movable switch means to engage said clutch sections when the switch means is moved into engagement with one of the contacts, the last mentioned means comprising an electro-magnet controlled by the switch means.

6. In an automatic emergency selective switch, a suitable frame, a conductor having a plurality of contacts spaced apart, movable operating means operable to selectively engage the contacts, means tending to actuate the switch means to open the same, a trip operable to trip the locking means, the trip being normally arranged in a predetermined starting position and having means for returning it to starting position, an electric motor, motion transmitting means between the motor and the trip to actuate the trip along the series of contacts when the trip is in operated position, the trip comprising normally separated clutch sections and means tending to separate them, and means controlled by the switch means to engage said clutch sections when the switch means is moved into engagement with any one of said contacts.

In testimony whereof, I have hereunto signed my name, at Syracuse, in the county of Onondaga, and State of New York, this 8th day of June, 1928.

CARL H. BISSELL.
